Attorney.

UNITED STATES PATENT OFFICE.

CHARLES A. STICKNEY, OF CHICAGO, ILLINOIS.

TELEPHONE COIN-BOX.

1,254,168.

Specification of Letters Patent. Patented Jan. 22, 1918.

Application filed May 15, 1916. Serial No. 97,681½.

To all whom it may concern:

Be it known that I, CHARLES A. STICKNEY, a citizen of the United States, and a resident of Chicago, in the county of Cook and 5 State of Illinois, have invented certain new and useful Improvements in Telephone Coin-Boxes, of which the following is a specification.

One object of my invention is to provide 10 means in a telephone coin box, whereby the subscriber depositing a coin maintains control of the coin until the connection called for by him is completed.

Another object of my invention is to provide 15 in a telephone coin box means whereby the coin is deposited by the central office, the control being either manual or automatic, but the return of the coin is entirely under control of the local station.

20 With these and incidental objects in view the invention consists of certain novel features of construction and combination of parts, the essential elements of which are hereinafter described with reference to the 25 drawing which accompanies and forms a part of this specification.

In the drawing Figure 1 is a schematic 30 view of the circuit of my improved coin box, Fig. 2 being a front elevation with the cover removed. Fig. 3 is a section taken on the line "A A", Fig. 2. Fig. 4 is a section taken 35 on the line "B B", Fig. 2.

The coin deposited by the subscriber in 40 the slot 1, Fig. 3, passes in the coin chute 2, 35 Figs. 2 and 3, to the position shown at 3.

The armature 4, Fig. 3, carries thereon a 45 pin 5, solidly mounted in the armature in any suitable manner, a pin 6, horizontally pivoted in the armature, and a pin 7 carried 50 by the punching 8, which is insulated from the armature and is brought out to the circuit by the terminal 9.

The closing of the contact between the 45 pins 6 and 7 is adapted to set up certain circuit conditions, as will hereinafter be more fully explained.

A pair of coils 10 polarized by the permanent magnet 11 and mounted in any suitable 50 manner to the frame is adapted to tilt the armature one way or the other, depending upon the direction of the current flowing therein, and when the armature is tilted to the left, as shown in Fig. 3, the coin will be deposited through the chute 11' to the coin 55 box 12, Fig. 2, while if it is tipped to the right, as shown in Fig. 3, the coin will pass

through the returning chute 13, Fig. 2, and be received in the finger 14, Figs. 2 and 3, where the subscriber may receive it.

The coils 10 are so wound that they will 60 not operate on 24 volts applied to the line at central exchange, or whatever the voltage may be on the exchange system, but will operate with 110 volts direct current from the 65 exchange.

The returning coil 15, Fig. 3, operates on the upper part of the armature when actuated, drawing the armature right-handedly, as shown in Fig. 3, to restore the coin 70 through the finger 14, as already described.

The line wire 16, Fig. 1, passes through a switch hook contact 17, through wire 18 to the returning coil 15, wire 19, pins 7 and 6, when the coin is carried by the pins 5 and 6 at 3, through the frame of the box to the 75 ground at 20, and this coil is adapted to actuate the returning mechanism through the ordinary line current, hence the coin will always pass through the box to the returning finger 14 if the switch hook contact 17 80 is closed, and if after the subscriber has removed his receiver and made the call in the ordinary manner he decides not to wait for the connection and hangs his receiver back on the hook the coin will be immediately 85 returned to him.

However, if by any means, mechanical or automatic, 110 volt current of proper polarity is sent through depositing coils 10, the coin 90 will be deposited in the coin box 12, and of course will then be out of the control of the subscriber.

If means are provided at the central office for sending two polarities of 110 volt current the coin could be returned to the subscriber by the operator without his hanging his receiver upon the hook, but I prefer to use with this box a circuit similar to the one shown in my co-pending application No. 97,680½, filed May 15, 1916, for improvements 95 in telephone exchange apparatus, wherein the depositing and returning of the coin is entirely out of control of the operator, and with this box the depositing would depend entirely upon the completion of the connection, while the returning would depend upon the hanging up of the subscriber at any time before the connection had been completed.

It is of course evident that the same result 100 might be obtained through a mechanical connection between the switch hook and the returning armature, but this would manifestly 110

be within the scope of my invention, as I believe myself to be the first to devise means for returning a coin to the subscriber at any time he desires before it is deposited, in combination with means controlled by either the central exchange or the called subscriber for depositing the coin in the coin box, and claim this combination broadly.

While I have described my invention and illustrated it in one particular design, I do not wish it understood that I limit myself to this construction, as it is evident that the application of my invention may be varied in many ways within the scope of the following claims.

Claims:

1. In a telephone coin box associated with a telephone having a switch hook and electrically connected with a central exchange, the combination of a money box, a coin chute, an armature pivoted along one axis, polarized electromagnetic means co-acting to oscillate said armature in either direction depending upon the direction of current flow in said electromagnetic means, non-polarized electromagnetic means also associated with

said armature and co-acting therewith to oscillate said armature in one direction only, means on said armature for normally preventing a coin from passing from said coin chute and adapted to release such coin when said non-polarized electromagnetic coil is actuated.

2. In a telephone coin box associated with a telephone station having therein a switch hook contact and electrically connected with a central office exchange, the combination of a coin chute, a money box, a return finger, an armature pivoted for oscillation in either direction, polarized electromagnetic means for oscillating said armature in either direction, non-polarized electromagnetic means controllable by said switch hook contact for moving said armature in one direction, means on said armature for preventing the passing of a coin from said coin chute when said armature is normally positioned to release said coin for passage to said return finger when said armature is actuated by said non-polarized electromagnetic means.

Copies of this patent may be obtained for five cents each, by addressing the "Commissioner of Patents, Washington, D. C."

CHARLES A. STICKNEY.
